UNITED STATES PATENT OFFICE.

FRANK C. DELI, OF CHICAGO, ILLINOIS, ASSIGNOR, BY MESNE ASSIGNMENTS, TO AUTOPOINT COMPANY, OF CHICAGO, ILLINOIS, A CORPORATION OF ILLINOIS.

PENCIL.

Application filed October 3, 1921, Serial No. 504,839. Renewed July 13, 1925.

To all whom it may concern:

Be it known that I, FRANK C. DELI, a citizen of the United States, residing at Chicago, in the county of Cook and State of Illinois, have invented certain new and useful Improvements in Pencils, of which the following is a specification.

This invention relates to a pencil wherein is contained a propelling mechanism for ejecting a lead as required for use. In particular my invention is concerned with certain improvements in such mechanism, and in the construction of the pencil body within which the same is contained. It is concerned further with a novel process for producing a pencil body of such construction.

An exemplification of my invention in its preferred form is shown in the accompanying drawing, wherein—

20 Figure 1 is a longitudinal section through the pencil, taken on line 1—1 of Fig. 3;

Fig. 2 is a side elevation of one of the two sections forming the pencil body, the view looking towards its inner face;

25 Fig. 3 is an enlarged transverse section taken on line 3—3 of Fig. 1; and

Fig. 4 is a view in elevation of the propelling mechanism detached from the body.

In the drawing the pencil body is designated as A, and by preference its upper end is slotted as at 4 and reduced slightly as at 5, and over the pencil end thus rendered compressible is fitted a sleeve 6 in which is retained an eraser 7. This sleeve is tightly but

30 removably secured to the body, and when detached therefrom exposes the upper end of a chamber 8 which is formed in the upper region of the pencil to provide a compartment for reserve leads. The walls compos-

35 ing the pencil body are transversely extended as at 9, thus forming a bottom for the chamber. Extending downwardly from the transverse walls 9 to the lower end of the pencil body is a central bore 10 which is en-

40 larged throughout its lower region 11 to provide a cylindrical opening of somewhat greater diameter. The upper region of this bore is formed with diametrically opposite slots 12, best shown in Fig. 3, extending

45 away from each other a distance about equal to the diameter of the enlarged portion 11 of the bore. At the juncture of the two bore portions 10 and 11 the surrounding walls

are gradually inclined at 13, tapering from a cylindrical contour in the lower region to a slotted contour thereabove. At its lower extremity the pencil body is formed with an external recess 14 in a manner similar to the construction at its upper end.

A propelling mechanism B, which is adapted for association with a pencil body formed as above described, may comprise a tapered sleeve 15 having a cylindrical upper end as at 16 so as to fit snugly upon the recessed lower end of the pencil. At the lower end of the tapered sleeve 15, which constitutes a tip for the pencil, is a central opening through which is projected the active lead C. Mounted fast within the sleeve 15 is a tube 17 arranged concentric to the pencil body in such a manner as to lie within the enlarged portion 11 of its bore. This tube 17 is provided with spiral convolutions 18 in the form of a thread, and is adapted to receive within itself a plunger 19 near whose lower end are one or more laterally projecting teeth 20 which may conveniently be formed by the action of a die. The teeth so formed are adapted to engage with the tube threads 18 which result from the formation of the spiral convolutions in its walls. At its upper end the plunger 19 is provided with a flattened head 20 which is laterally extended to present its edges within the oppositely disposed slots 12, thus preventing the plunger from rotation within the pencil body.

The specific construction of the tube and plunger form no part of the present invention, but are claimed in a co-pending application, Serial No. 758,831, of December 30, 1924.

To effect propulsion of the lead, the pencil tip 15 is rotated relative to the body, and because of the nonrotative mounting of the plunger therewithin the spiral threads in the tube 18 will cause the plunger to be moved longitudinally against the lead to expel the same through the tip. When the active lead has been used to its effective limit, the entire propelling mechanism B may be detached from the body, the plunger unscrewed from the tube, and a new lead inserted therein, following which the plunger is reassembled within the tube sufficiently to engage with the threads 18. The

entire propelling mechanism is thereafter replaced upon the pencil in the relationship shown in Fig. 1.

In a pencil such as is herein described, the body may be made of any suitable material, and be produced according to any convenient method. My invention, however, contemplates the production of a body having characteristics such as have been heretofore noted, and which is formed from a composition material that can be moulded within suitable dies; it contemplates, furthermore, the production of a body from some such material by a method which possesses special advantages. This phase of my invention will now be explained in detail.

The material suggested for the body of a pencil such as is shown in Figs. 2 and 3 is preferably a composition that becomes plastic under the application of heat and pressure. Such materials are commercially available under the names of bakelite, redmanol, etc. The first step in forming the body from some such material is to mould a one-half section thereof, the same as is shown in Fig. 2. Two such sectional halves are produced from composition material, each having, by preference, a member in the nature of a tongue 25 and a groove 26 which is complementary thereto (see Fig. 3). When so formed the two sections may be fitted one upon the other with the tongues interlocking with the grooves so as to center the two parts together.

Any other convenient interlocking means may be employed, however, but the one suggested will be found particularly convenient, inasmuch as it permits the use of but a single mould for the making of the two sectional halves, the one being a counterpart of the other. When the two body sections thus produced are fitted one upon the other, they are then placed in a new mould, which is thereafter subjected to the action of heat and pressure. The effect of this is to sufficiently soften the two body sections to unite them permanently together as though moulded in a single operation. During this last heat treatment, the temperature is preferably raised to the necessary point to set the material, thereby precluding any possibility of its softening again.

A pencil produced according to the method just described may be finished in a very attractive manner and will possess the desirable qualities of strength and lightness. To the eye it will not be apparent that the body is formed of two united sectional halves, since the lines of juncture therebetween are

practically obliterated through the practice 60 of the method just described. By properly designing the moulds, the interior faces of the body are made to correspond with the construction shown in Fig. 1. It will be noted that the transverse wall 9 therein 65 shown is provided in Fig. 2 by forming a button 27 on each body section, these two buttons co-operating to provide a bottom for the compartment 8.

The method of moulding disclosed herein 70 is broadly claimed in the copending application of Kaufman, Lynn and myself, Serial No. 612,617, filed January 15, 1923.

The invention herein disclosed presents 75 dual aspects, one having to do with the construction of the pencil itself, and the other with the method employed in such construction. It is to be presumed that changes in modification from the exact form and method described may be made without 80 sacrifice of the features which impart novelty to my invention, and such as are defined by the appended claims are deemed to be covered by the patent issuing hereon.

I claim:

1. A pencil body formed of a composition material and consisting of two duplicate sections each of the length of the body, and means integral with the sections for centering the same relative to each other, the two sections being united to form a completed body.

2. A mechanical pencil body consisting of a plurality of fractional portions each of which is a duplicate of another and each 90 of which is provided with a tongue and a groove, said fractional portions being united to form a unitary body.

3. A mechanical pencil body composed of two portions each of which is complementary to and a duplicate of the other, the meeting faces of said portions being provided with reciprocal projections and recesses for effecting accurate mating relation, said portions being joined to form a unitary 100 structure.

4. A longitudinally recessed pencil body composed of two portions each of which is complementary to and a duplicate of the other, the meeting faces of said portions being provided with reciprocal projections and recesses for effecting accurate mating relation, said portions being joined to form a unitary structure, the longitudinal recess being divided by a transverse wall to provide two compartments.

FRANK C. DELI.
